UNITED STATES PATENT OFFICE.

GREGORY C. DAVISON, OF GROTON, CONNECTICUT.

DEPTH-CHARGE PROJECTOR.

1,323,162.

Specification of Letters Patent. Patented Nov. 25, 1919.

Application filed September 12, 1918. Serial No. 253,737.

To all whom it may concern:

Be it known that I, GREGORY C. DAVISON, a citizen of the United States, residing at Groton, in the county of New London and 5 State of Connecticut, have invented certain new and useful Improvements in Depth-Charge Projectors; and I do hereby declare the following to be a full, clear, and exact 10 description of the invention, such as will enable others skilled in the art to which it appertains to make and use the same.

My present invention relates to improvements in depth charge projectors, and it is intended to provide a projector or gun having 15 a single barrel, and adapted to project the depth charge through a short range in any desired direction in azimuth.

A similar construction is shown in the depth charge projector commonly known as 20 the "Y" gun, illustrated and described in the application of Andrew J. Stone, Serial No. 192130, filed September 19, 1917, and entitled Improvements in depth charge projectors; but in that particular construction 25 the gun is not intended to be trained in azimuth and the two projectiles were simultaneously fired from the two divergent barrels.

The purpose of the present invention is 30 to provide a single barrel depth bomb projector which will throw only one projectile at a time, and yet which can be trained in azimuth as desired.

My invention will be more fully understood after reference to the accompanying 35 drawings, in which similar parts are indicated by similar reference symbols throughout the several views, and in which:—

Figure 1 is a plan view of the projector 40 and its mount.

Fig. 2 is a front elevation of the same, the deck of the vessel being shown in section; and

Fig. 3 shows a central, vertical section 45 through the axis of the bore and powder chamber, parts being shown in elevation, and the projectile being shown as supported in the gun.

A represents the projector or gun, having 50 its forward portion or barrel tapered upward, as at a , and its rear portion horizontal, as at a' , and provided with an enlarged expansion chamber a^o for the powder gases.

The breech of the piece is provided with a 55 similar powder chamber a^2 into which the cartridge case B is mounted. The powder

chamber is closed by any suitable breech mechanism X. I have shown in the drawings a breech mechanism somewhat similar to that shown in the patent application of 60 A. J. Stone aforesaid, and as no claim is made to any special form of mechanism in my present application, the breech closure will not be further described.

C represents the bed plate on which the 65 piece is mounted, which bed plate is secured to the deck of the vessel in any convenient way, as by means of bolts D.

This bed plate is provided with a tapered socket C^o to receive the tapered lug A' projecting downward from the body of the projector. A washer A² is attached to the base 70 of the lug A' by means of the bolt A³ and serves to prevent the projector from being thrown out of its engagement with the bed 75 plate when the vessel carrying the projector rolls heavily.

Mounted between the bed plate and the conical surface a^3 of the projector I provide 80 a series of rollers E, mounted in the ring F, which provide an anti-friction bearing or traverse for the piece. In order to balance the projector when loaded, I provide a heavy weight G to which is connected a socket plate H to serve as a bearing for the 85 training bar I, which training bar may be inserted or removed when desired, by means of which the piece is trained in azimuth.

In order to lock the projector against 90 swinging about its pivot, when not in use, I provide a bolt J having a tapered hole to receive the tapered locking bolt K, which engages a recess c in the bed plate C. Several of these recesses c may be provided so 95 that the piece may be locked at any desired position in azimuth; but when in use the gun pointer at the training bar I can keep the piece properly pointed.

The locking bolt K may be secured to any 100 convenient part of the mount by the chain L, so as to prevent it from being lost.

M represents the bomb or case containing the depth charge, which is secured to the holder N, which holder is provided with a 105 hollow stem or piston N', which projects into the inclined barrel a and serves as a piston against which the powder gases act under pressure when the cartridge has been fired.

To project quite a heavy bomb from the 110 piece only a small charge of powder will

suffice; and the powder gas expanding in the expansion chamber a^o will start the piston N' outward without any excessive shock when the piece is fired. This projector is 5 not intended to fire the bomb through any great range, or with any large initial velocity, nor with any great accuracy, for the danger zone from the explosion of one of these bombs is quite extensive, and moreover 10 the target is rarely visible, so that neither great range nor great accuracy are desired.

In such cases where the target is visible, or greater range is desired, high explosive shell from high power guns should preferably 15 be resorted to.

In operating the device, the locking bolt is removed, the stem N' of the holder N is inserted in the barrel, the cartridge containing the powder charge is inserted in the 20 breech, and the piece is trained by the gun pointer as accurately as practicable in the direction in which it is desired to project the bomb; and the cartridge is then fired and the bomb with its holder expelled.

25 The operation of re-loading and firing the gun may be continued indefinitely.

When it is desired to "secure" the piece, it is swung in azimuth until the locking bolt K can be inserted in one of the recesses e 30 in the bed plate. The piece will then be held against swinging about its pivot.

The training bar I may be allowed to remain in place or may be removed when the piece is secured, as preferred.

35 Since low pressures only are required, the main body of the projector may be made of cast metal, such as cast iron or steel, or bronze. Moreover, very little machining is required, so that the device may be quickly 40 and cheaply manufactured in large quantities; and when the emergency is over the body portion of the projectile and the counter weight without material loss can be scrapped and used for other purposes.

45 It will be obvious that various modifications might be made in the herein described apparatus and in the construction, combination and arrangement of parts which could be used without departing from the spirit 50 of my invention; and I do not intend to be limited to such details except as particularly pointed out in the claims.

Having thus described my invention what 55 I claim and desire to secure by Letters Patent of the United States is:—

1. In a depth charge projector, the combination with a gun having an upwardly inclined barrel and a horizontally disposed expansion chamber at the base of and forming 60 a continuation of the bore of said barrel, and a cartridge chamber of smaller diameter than said expansion chamber connected to said expansion chamber, the bottom of the gun body being provided with an annular shoulder, and a downwardly pro-

jecting lug concentric with said shoulder, of a bed plate secured to the gun platform beneath the gun and provided with a socket to receive said lug and with an annular shoulder registering with the annular shoulder of the gun body, with antifriction rollers interposed between said shoulders, substantially as described. 70

2. In a depth charge projector, the combination with a gun having an upwardly inclined barrel and a horizontally disposed expansion chamber at the base of and forming a continuation of the bore of said barrel, and a cartridge chamber of smaller diameter than said expansion chamber connected to 75 said expansion chamber, the bottom of the gun body being provided with an annular shoulder, and a downwardly projecting lug concentric with said shoulder, of a bed plate secured to the gun platform beneath the gun and provided with a socket to receive said lug and with an annular shoulder registering with the annular shoulder of the gun body, with antifriction rollers interposed between said shoulders, substantially as described. 80

3. In a depth charge projector, the combination with a gun having an upwardly inclined barrel and a horizontally disposed expansion chamber at the base of and forming a continuation of the bore of said barrel, and a cartridge chamber of smaller diameter than said expansion chamber connected to 85 said expansion chamber, the bottom of the gun body being provided with an annular shoulder, and a downwardly projecting lug concentric with said shoulder, of a bed plate secured to the gun platform beneath the gun and provided with a socket to receive said lug and with an annular shoulder registering with the annular shoulder of the gun body, with antifriction rollers interposed between said shoulders, and a counterweight secured to the gun body near its breech, substantially as described. 90

4. In a depth charge projector, the combination with a gun having an upwardly inclined barrel and a horizontally disposed expansion chamber at the base of and forming a continuation of the bore of said barrel, and a cartridge chamber of smaller diameter than said expansion chamber connected to 95 said expansion chamber, the bottom of the gun body being provided with an annular shoulder, and a downwardly projecting lug concentric with said shoulder, of a bed plate secured to the gun platform beneath the gun and provided with a socket to receive said lug and with an annular shoulder registering with the annular shoulder of the gun body, with antifriction rollers interposed between said shoulders, and a counterweight secured to the gun body near its breech, substantially as described. 100

5. In a depth charge projector, the combination with a gun having an upwardly inclined barrel and a horizontally disposed expansion chamber at the base of and forming a continuation of the bore of said barrel, and a cartridge chamber of smaller diameter than said expansion chamber connected to 105 said expansion chamber, the bottom of the gun body being provided with an annular shoulder, and a downwardly projecting lug concentric with said shoulder, of a bed plate secured to the gun platform beneath the gun and provided with a socket to receive said lug and with an annular shoulder registering with the annular shoulder of the gun body, with antifriction rollers interposed between said shoulders, and a counterweight secured to the gun body near its breech, substantially as described. 110

6. In a depth charge projector, the combination with a gun having an upwardly inclined barrel and a horizontally disposed expansion chamber at the base of and forming a continuation of the bore of said barrel, and a cartridge chamber of smaller diameter than said expansion chamber connected to 115 said expansion chamber, the bottom of the gun body being provided with an annular shoulder, and a downwardly projecting tapered lug concentric with said shoulder, of a socket bearing provided in the gun platform to receive said lug, and an annular track carried by the gun platform, and registering with the annular shoulder of the gun body, substantially as described. 120

7. In a depth charge projector, the combi- 125

nation with a gun having an upwardly inclined barrel and a horizontally disposed expansion chamber at the base of and forming a continuation of the bore of said barrel, 5 and a cartridge chamber of smaller diameter than said expansion chamber connected to said expansion chamber, the bottom of the gun body being provided with an annular shoulder, and a downwardly projecting ta-

pered lug concentric with said shoulder, of 10 a socket bearing provided in the gun platform to receive said lug, an annular track carried by the gun platform, and registering with the annular shoulder of the gun body, and a counterweight secured to the gun body 15 near its breech, substantially as described.

GREGORY C. DAVISON.
